UNITED STATES PATENT OFFICE.

RAY E. DUNHAM, OF BEREAL, OHIO, ASSIGNOR TO THE DUNHAM COMPANY, OF BEREAL, OHIO, A CORPORATION OF OHIO.

TILLAGE IMPLEMENT.

Application filed March 1, 1923. Serial No. 622,012.

My invention relates to improvements in tillage or earth working implements, the present embodiment of the invention relating more particularly to that class or type of implement commonly known as "soil pulverizers" in which gangs of pulverizing or "packer" discs are employed, said discs having their outer or soil engaging portions oppositely curved and terminating in cutting edges and abutting against each other so that the curved portions of the adjacent discs conjointly form intervening soil packing ridge forming grooves.

In earth working or tillage implements of the class indicated, it is not only desirable that considerable weight or ballast be employed to thoroughly pulverize and pack the subsurface, but it is particularly desirable that means be provided whereby to vary such weight or ballast in accordance with varying soil conditions to be met in actual service. Furthermore, in implements of the specific class mentioned it follows that the necessary or desirable weight required to give proper service under ordinary soil conditions is such that the freight or transportation charges are considerable, particularly where the transportation distance is relatively great.

My improvements therefore relate to improved means for ballasting a tillage implement of the general specific character mentioned through the medium of a suitable liquid, such as water, or the like, and whereby such liquid ballast may be readily varied to correspondingly vary the weight transmitted through the tillage elements or soil pulverizing packer wheels to meet the particular soil demands or conditions of the particular soil being cultivated or operated upon.

In carrying out my invention I therefore provide a suitable liquid carrying member or container of the requisite capacity to give the desired weight and to vary the same within the ordinary limits and soil conditions to be met as above referred to. In an implement of the specific character mentioned I preferably provide a hollow drum shaped liquid ballasted body rotatably mounted and adapted to loosely carry and support the gangs of earth working elements or packer discs in lieu of the gang axle shaft ordinarily used for such purpose, suitable means being provided for holding and variably spacing

such earth working elements or packer discs in properly spaced abutting relation and whereby certain predetermined pulverizer or packer discs may be removed from the liquid ballasted body drum and the remaining 60 packer discs be secured in certain predetermined positions apart to provide suitable spaces or passes to receive rows of growing crops.

There are other features of the invention 65 residing in elemental combinations and particular construction of parts, all as will hereinafter more fully appear.

With the above mentioned and other ends in view, the invention consists in the novel 70 construction, arrangement and combination of parts, hereinafter described, illustrated in some of its embodiments in the accompanying drawings, and particularly pointed out in the appended claims.

Referring to the accompanying drawings, forming a part of this specification, Figure 1 is a fragmentary side elevation, partly in section, of a gang of pulverizer discs and a liquid ballasted body drum, constructed in 80 accordance with this invention, and detached from the implement or draft frame and its bearings.

Fig. 2, a similar view of the median or intermediate portion of the same, illustrating 85 in particular a suitable means, such as a spacing clamp or collar, for spacing certain of the pulverizer discs a predetermined distance apart to form a space or pass to receive a row of growing crops, such as corn, or the 90 like, and whereby the soil between such rows may be cultivated or packed and mulched.

Fig. 3, a cross sectional view of the same taken on line 3—3 of Fig. 2.

Fig. 4, an end elevation of one of the disc 95 gangs and illustrating in particular one of the end bearing heads of the liquid ballasted body together with suitable means for holding or securing the tillage elements or pulverizer discs in properly spaced abutting 100 relation in the gang.

Fig. 5, a cross sectional view of a disc gang embodying a modified form of liquid ballasted body.

Similar numerals of reference designate 105 like parts throughout all the figures of the drawings.

The gangs of earth working elements or pulverizer discs may be arranged in any suitable and convenient manner and so like- 110

wise the gangs may be mounted in any suitable manner in draft or implement frames of any suitable construction, and such parts and features of construction forming no part 5 of the present invention need not be shown or described in detail.

As a means of providing a suitable supply of liquid ballast, such as water or the like, and particularly as a means of varying such 10 ballast to correspondingly vary the weight transmitted to and through the tillage elements or pulverizer discs in accordance with the character of the particular soil being cultivated or treated, a hollow liquid carrying 15 body is provided, which, in the present instance, is in the specific form of a rotary drum provided with suitable bearing heads and axles for use in lieu of the ordinary gang shafts heretofore used in holding and 20 supporting the gangs of packer or pulverizer discs in properly spaced rotatable relation to each other.

Such rotary liquid ballasted body may be of any suitable and convenient form and, in 25 the present instance, comprises suitable bearing heads 1, secured to suitable cylindrical walls 1^a, the parts 1 and 1^a conjointly forming a rotary drum or cylinder providing an interior liquid or water chamber 1^b. The 30 ends or heads 1 are preferably provided with gudgeons or stub axle shafts 1^c, adapted to be mounted in suitable bearings in any suitable implement frame.

The earth working elements in the specific 35 form of pulverizer or packer discs preferably comprise the usual approximately V-shaped rims made up of the concave exterior faces or treads 2, meeting in an apex forming a soil cutting or dividing head 2^a, said rim portions being similar to the soil engaging portions of the pulverizer or packer discs heretofore employed in implements of this 40 specific character. The packer discs 2, are loosely and rotatably mounted on the walls 1^a of the body drum and in abutting relation to each other, being preferably provided with relatively wide annular base bearing portions 2^b, to form suitable annular bearings around the walls of the drum, the treads 45 2 conjointly forming intervening soil packing ridge forming grooves 2^c.

As a means of quickly and conveniently mounting the packer discs upon or removing the same from the drum, the ends of the latter are preferably provided with packer disc retaining rims 3, in the present instance surrounding the bearing heads 1, and as a means of removably securing said rims 3 in position, the ends of the heads are preferably provided with clamps 4, mounted in guide lugs 1^d of the heads and secured by means of clamp bolts 5, and nuts 5^a.

As a means of inserting the water or ballast liquid into or removing the same from 50 the drum, the outer periphery or wall 1^a

thereof is preferably provided near one end with a threaded opening 1^e, adapted to be opened and closed by means of a suitable threaded plug 1^f. It will be apparent that by varying the amount of water or liquid in 70 the chamber 1^b, the weight of the ballast will be correspondingly varied thereby correspondingly varying the weight transmitted to and through the tillage elements or discs 2.

As a means of variably spacing the tillage elements or packer discs 2 on the water ballasted drum 1^a, and particularly as a means of removing one or more of such discs or elements 2 and rearranging the remaining discs or elements at certain predetermined distances apart to provide a suitable space or pass to receive a row of growing crops, suitable disc separating clamps 6, may be provided, said clamps being adapted to surround the walls 1^a of the drum and, in the present instance, being made up of two parts adapted to be connected by means of connecting bolts or pins 6^a.

Upon reference to the modified form of 90 disc carrying drum shown in Fig. 5 of the drawings, it will be seen that such drum is provided with longitudinally extending corrugations 1^g, forming the intervening groove portions and the raised or crest portions 1^h, the latter only being engaged by the bearing portions of the packer elements 2 thereby reducing the bearing surface and friction as 95 compared with the form shown in Figs 1 to 4, inclusive, of the drawings.

Moreover, by corrugating the drum surface, provision is made for allowing a certain amount of expansion in the drum wall as a provision against the bursting of the drum due to freezing of water which may remain in the drum during the winter weather.

By reason of the above described construction, it will be apparent that the drums are shipped empty and are not provided with water ballast until it is desired to use the same and that then the amount of ballast or weight introduced will be governed by the particular soil conditions of the particular locality where the implement is to be used and it will also be apparent that on direct draft the soil pulverizing elements or packer discs 2 will rotate with the drum 1^a and simultaneously with each other and that upon making turns to one side or the other such elements 2 will rotate independently and relatively of each other and to the said drum 1^a.

Having thus described one of the embodiments of my invention without having attempted to set forth all the forms in which it may be made, or all the modes of its use, what I claim and desire to secure by Letters Patent is,—

1. In a tillage implement, the combination of a rotatably mounted body provided

with a plugged aperture for the introduction of liquid ballast, and a plurality of V-shaped treads in the form of rings, rotatably mounted upon the body and in laterally adjacent relation to one another, the walls of the body being provided with longitudinal corrugations, substantially as described.

2. In a tillage implement, the combination of a rotatably mounted body provided with a plugged aperture for the introduction of liquid ballast, and a plurality of radially projecting treads in the form of rings, rotatably mounted upon the body and in laterally adjacent relation to one another, the walls of the body being provided with longitudinal corrugations, substantially as described.

3. In a tillage implement, the combination of a drum shaped body consisting of ends and a connecting side wall provided with longitudinally extending corrugations, the body being provided with a plugged aperture for the introduction of liquid ballast, and a plurality of V-shaped treads in the form of rings surrounding the body and contacting the crests of the corrugations thereon, and being rotatable with respect thereto, said treads standing in laterally adjacent relation to one another to afford intervening grooves between the cutting edges of the adjacent treads, substantially as described. 20 25 30

In testimony whereof I have affixed my signature.

RAY E. DUNHAM.
